UNITED STATES PATENT OFFICE.

VINCENT SCHOFIELD WICKHAM, OF WORCESTER, MASSACHUSETTS.

APPARATUS FOR TRIMMING ODONTOLOGICAL CASTS.

1,331,302.

Specification of Letters Patent.

Patented Feb. 17, 1920.

Application filed March 21, 1919. Serial No. 284,007.

To all whom it may concern:

Be it known that I, VINCENT SCHOFIELD WICKHAM, a citizen of the United States, residing at Worcester, in the county of Worcester and Commonwealth of Massachusetts, have invented a new and useful Improvement in Apparatus for Trimming Odontological Casts, of which the following, together with the accompanying drawings, is a specification.

My present invention relates to an apparatus for trimming the plaster casts employed by dentists representing the upper and lower sets of teeth as represented in perspective view in Fig. 1, the cast containing the teeth of the upper jaw being termed the capital and that containing the teeth of the lower jaw being termed the base. These casts, when taken from the mold or impression tray, are more or less rough and irregular and require to be carefully trimmed both on the upper and lower surfaces and around their edges. This trimming, so far as I am aware, is universally performed by hand, the operator holding the cast and trimming it with a knife, with the result that the trimming is more or less irregular and the desired outline is difficult of attainment.

It is the purpose of my present invention to provide an apparatus provided with adjustable means for holding the casts in proper position to be trimmed and for guiding the knife in the operation of trimming, whereby those portions of the cast to be removed may be definitely and accurately determined. These objects, among others, I accomplish by means of an apparatus illustrated in the accompanying drawings, in which—

Figure 1 is a perspective view of the completed casts containing the teeth of the upper and lower jaws.

Fig. 2 is an outline of a cast when released from the mold or impression tray.

Figs. 3 and 4 represent in outline the upper and lower casts respectively after the same have been trimmed.

Fig. 5 is a plan view of the holding frame with the parts in position for trimming side No. 1, Fig. 4.

Fig. 6 is a view similar to Fig. 5 with the parts in position for trimming side No. 2, Fig. 4.

Fig. 7 is a side elevation of the holding

frame with a portion shown in section on the plane of the broken line 7—7, Fig. 5, and

Fig. 8 is a detail view showing the shoulder which forms the guide for the reciprocating chisel.

60

Similar reference characters refer to similar parts in the different figures.

Referring to Fig. 1 of the drawings, *a* represents the upper cast or capital and *b* the lower cast or base in their completed form, 65 and *c*, Fig. 2, represents in outline the form of both capital and base as taken from the mold. The casts have the outline shown at *c*, Fig. 2, are trimmed upon their upper surfaces to form the capital and upon their 70 lower surfaces to form the base. Each cast is then trimmed upon its edges in the shapes represented in Figs. 3 and 4, that represented in Fig. 3 being trimmed upon the edges 1, 2, 3, 4, 5, 6 and 7, and that represented in Fig. 4 being trimmed upon the edges 1, 2, 75 3, 6 and 7.

In Figs. 5 and 6 I have represented in plan view a holding frame for the plaster casts, provided on one edge with a shoulder 80 serving as a guide for a manually operated knife and containing an adjustable cutter for smoothing the upper and lower edges of the casts. The holding apparatus consists of a plate preferably having a wooden base *d*, 85 Fig. 7, covered on its upper surface with a plate of sheet metal *e*. The plate *d* is rabbed at one edge to form a shoulder *f* and base *g* as represented in Fig. 8, over which the metal plate *e* is extended. An opening *h*, 90 Figs. 5 and 7, is formed through the plate to receive a cutting knife *i* placed at an oblique angle to the surface of the plate, said opening *h* being enlarged at the bottom as shown at *j* for the free release of the portions of the cast as the latter is reciprocated back and forth over the edge of the cutting knife *i* in trimming the broadside surfaces of the casts, which is the first operation in trimming. The position of the cast during 95 this operation is shown at *c*, Fig. 7. Upon the top of the holding plate I pivot a bar *k* by means of a bolt *k'* held in the plate and carrying a wing nut *k''* by which the bar *k* may be tightened in any desired position.

The opposite end of the bar *k* carries a bolt *k''* having an enlarged head which is movable in an undercut groove *k''* concentric with the bolt *k'*, said groove *k''* communicating with a similar undercut groove *k''* par- 100 105 110

allel with the edge l of the holding plate. The bar k is provided with a longitudinal undercut slot k^6 . Crossing the bar k is a similar bar m having an undercut slot m' , and connecting the two bars k and m is a bolt m^2 sliding freely in the slot k^6 of the bar k and passing through the slot m' of the bar m . The bolt m^2 carries a wing nut m^3 , enabling the two bars k and m to be locked together. The bolt k^3 is provided with a wing nut k^7 , and held in the slot m' is a bolt m^4 having an enlarged head movable in the undercut slot k^4 and provided with a wing nut m^5 .

15 In Fig. 5 I have shown a cast c represented by broken lines in a position for trimming the broadside of the cast by its movement over the knife i , and I have also shown the outline of a cast c in position for trimming the edge 1, with the bars k and m placed in position for supporting the cast c against movement as the edge 1 is being trimmed. The bars k and m are moved into proper position to contact with the curved surface of the cast c , with one edge of the cast overhanging the rabbeted edge n of the holding plate. A chisel pointed knife o is then reciprocated across the overhanging edge of the cast until the plastic material has been 30 cut away on a line corresponding with the rabbet n .

A readjustment of the bars k and m is then made, as indicated in Fig. 6, to afford suitable support to the cast c in position for 35 trimming the edge 2. For this purpose, the cast is made to overhang the rabbet n , as represented in Fig. 6, and the overhanging edge is then cutaway by the reciprocation of the chisel pointed knife o , the amount of 40 the plastic cast to be removed being determined by the overhang of the cast over the rabbeted edge n of the plate. Other adjustments of the slotted bars k and m are then made for the purpose of accurately trimming 45 the remaining edges 3, 4, 5, 6 and 7 of the casts. By the above method of trimming, great accuracy is secured in the trimmed casts, the only care required is in placing the casts with the proper overhang 50 of the casts over the rabbeted edge n .

I claim,

1. In an apparatus of the character described, a supporting plate for the cast, bars adjustable on said plate to contact with the 55 edges of the cast, and means for attaching

said bars to the plate in their adjusted positions.

2. In an apparatus of the character described, a supporting plate for the cast, bars adjustable on said plate to contact with the 60 edges of the cast, means for attaching said bars to the plate in their adjusted positions, and a guideway for a reciprocating knife.

3. In an apparatus of the character described, a supporting plate for the cast, bars 65 adjustable on said plate to contact with the edges of the cast, means for attaching said bars to the plate in their adjusted positions, said plate being rabbeted at one of its edges to form a guideway for a reciprocating 70 knife, and a knife inserted in said plate for trimming the broadside surfaces of the cast.

4. In an apparatus of the character described, a supporting plate provided with means for trimming the broadside surface 75 of a cast and having one of its edges rabbeted to provide a shoulder for a reciprocating knife, and means adjustable on said plate to contact with the edges of a cast.

5. In an apparatus of the character described, a supporting plate for the cast, means adjustable on said plate to contact with the edges of the cast, means for retaining said contacting means in their adjusted position, and a guide for a reciprocating 85 knife parallel with one of the edges of the plate.

6. In an apparatus of the character described, a supporting plate for the cast, a slotted bar pivotally attached at one end to 90 said plate and having its opposite end adjustably held in a slot concentric with the pivot of the bar, a second slotted bar adjustably held in the slot of said pivoted bar and having one of its ends adjustably held 95 on said plate.

7. In an apparatus of the character described, a supporting plate for the cast, a slotted bar pivotally held on said plate, said plate having a curved groove concentric 100 with the pivot of said bar and a straight line groove communicating with said curved groove, a second slotted bar crossing said pivoted bar, means for adjustably connecting said bars, and means for attaching said 105 second bar to said plate.

VINCENT SCHOFIELD WICKHAM.
